UNITED STATES PATENT OFFICE.

FRANCIS H. RICHARDS, OF HARTFORD, CONNECTICUT.

DESIGN FOR A FRAME FOR GRAIN-WEIGHING MACHINES.

SPECIFICATION forming part of Design No. 19,796, dated April 29, 1890.

Application filed March 28, 1890. Serial No. 345,778. Term of patent 14 years.

To all whom it may concern:

Be it known that I, FRANCIS H. RICHARDS, a citizen of the United States, residing at Hartford, in the county of Hartford and State 5 of Connecticut, have invented and produced a new and original Design for Machine-Frames, of which the following is a specification, reference being had to the accompanying drawings, forming part thereof.

10 In the drawings, Figure 1 is a plan or top view of a machine-frame embodying my design. Fig. 2 is an end elevation of the frame. Fig. 3 is a front elevation, and Fig. 4 a rear elevation, of the same.

15 Similar characters designate like parts in all the figures.

The leading features of my design reside in the upper portion of the frame shown in the drawings. The figure C, which is of a 20 box-shaped form, is set over one side, as seen

in end view, Fig. 2, of the columns or uprights N and N', and has the extension D reaching outwardly and downwardly. The connection between the figure or form C and the said uprights is by means of inclined or sloping surfaces, as 3, 4, and 5, which give to the whole structure a neat and distinctive appearance. 25

The frame-work herein shown and described is especially intended for grain-weighers and for those designated as "automatic," 30 being operated by the weight of the grain.

I claim—

The design for a grain-weighing machine-frame herein shown and described, substantially as set forth.

FRANCIS H. RICHARDS.
